UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP.

DOOR-HANGER.

No. 839,620.

Specification of Letters Patent.

Patented Dec. 25, 1906.

Application filed March 12, 1906. Serial No. 305,451.

To all whom it may concern:

Be it known that I, PHILIP A. MYERS, a citizen of the United States, residing at Ashland, in the county of Ashland and State of Ohio, have invented certain new and useful Improvements in Door-Hangers, of which the following is a specification, reference being had therein to the accompanying drawings.

10 This invention relates to door-hangers, and more particularly to that class known as "sliding barn-door hangers," in which the door is uninclosed and preferably free to swing around an axis extending horizontally 15 in the direction of travel of the door.

It is the object of my present invention to provide a construction whereby the door may be readily adjusted both vertically and laterally, so as to not only adjust or regulate 20 the height of the door relatively to the track on which it travels, but also the position of the door relatively to the building to which it is applied, so that the lower edge of the door may be brought into proper relation to 25 the floor, sill, or other surface over which it travels, while the body of the door may be moved toward and from the building, so as to cause it to travel in proper relation thereto.

Other advantages attendant upon my construction in its preferred form are that the wheel frame or support which constitutes the upper part of the hanger is free to turn or swivel around a vertical axis relatively to the lower part of the hanger, which is fixedly 35 connected to the door, so as to move in unison therewith, so that the said support or frame, with its wheel or wheels, is free to follow sinuosities of the track arising from accidental crookedness thereof; that the construction 40 is such that the adjusting devices in no wise interfere with the free lateral swinging of the door hereinbefore referred to, and that the structure is readily adapted to doors of different thickness.

45 To the attainment of these ends my invention consists in certain novel features, which I will now proceed to describe and will then particularly point out in the claims.

In the accompanying drawings, Figure 1 50 is a view showing in elevation a structure embodying my invention in one form. Fig. 2 is an enlarged detail sectional view. Fig. 3 is a view similar to Fig. 1, showing another embodiment of my invention. Fig. 4 is an

enlarged detail sectional view. Fig. 5 is a detail perspective view of the knuckle detached; and Fig. 6 is a detail sectional view of the lower part of the hanger, similar to what is shown in Figs. 2 and 4 except that the adjusting-sleeve is shown in full section.

Referring first to the construction shown more particularly in Figs. 1, 2, and 5, 1 indicates a building having a doorway 2 and door 3. 4 indicates a suitable track located above the doorway, on which the door-hangers which support the door travel. Ordinarily there are two of these hangers, as shown, located one near each end of the door. Each hanger comprises an upper portion, provided with a wheel to travel upon the track, and a lower portion, secured to the door and pivotally connected to the upper portion, so as to be free to swing relatively thereto around an axis parallel with the track. Referring first to the upper portion, it comprises a wheel support or frame 5, preferably in the form of a housing, in which is mounted a grooved wheel 6, adapted to fit and travel on the track 4. This wheel frame or support is also preferably provided with a guide lug or guard 7, which extends around the lower edge of the track and serves to prevent accidental derailment of the hanger. These parts so far as described may, however, be of any approved construction. The wheel-support has connected to it a vertically-adjustable threaded member or bolt 8, and in the particular construction now under consideration the wheel-support is provided with a threaded lug 9, in which the threaded member or bolt 8 fits and in which it is vertically adjustable by rotating either the bolt or support. The support is also preferably provided with a hollow cylindric boss or housing 10, which incloses and protects the upper end of the bolt. The lower end of the bolt is bent or deflected laterally, as indicated at 11, and terminates in an apertured lug 12, which when the parts are in their normal working position lies below and in the central plane of the track and wheel, as shown in Fig. 2. Referring now to the lower part of the hanger, it comprises two separate plates 13 and 14, located on opposite sides of the door, secured thereto by bolts 15 and extending, preferably, above the top of the door. In the upper end of one of these plates—for instance, the plate 13—there is mounted an adjusting-sleeve 16,

which is movable in the direction of its length through an aperture 17 in the plate 13 and which itself is provided with an internal aperture 18, extending longitudinally of its axis to receive a supporting-pin 19, which is secured to the other plate 14 and which extends across the space between the plates and preferably somewhat beyond the inner face of the plate 13. The adjusting-sleeve 16 has a threaded engagement with one of the two parts by which it is guided and supported—to wit, the plate 13 and pin 19—and in the present instance I have shown the said sleeve as threaded externally, the aperture 17 being correspondingly threaded to receive the same. The sleeve 16 is provided at its outer end with a wrench grasp-head 20 or other suitable means by which it may be readily rotated, while its inner end is provided with a circumferential groove 21 to receive the knuckle hereinafter described, which connects the lower portion of the hanger to the upper portion. The pin 19 may be secured to the plate 14 in any suitable manner—as, for instance, that shown, in which the pin passes through a suitable aperture in the upper end of the plate 14 and is provided on the inner side of said plate with a collar 22 to fit against the same, while its outer end is headed down or riveted against the outer face of the plate, as indicated at 23. Preferably the plates 13 and 14 are separate, and the sleeve 16 and pin 19 are made of a length sufficient to adapt them for use in connection with doors of different thickness, to which the separate plates may be readily applied. The lower portion of the hanger also comprises a knuckle, (indicated as a whole by the reference-numeral 24 and shown in detail in Fig. 5 of the drawings.) This knuckle at its lower end engages the groove 21 of the adjusting-sleeve 16, being preferably provided for this purpose with a loop or half-collar 25, which fits the lower and side portions of said groove. Said knuckle is pivoted to the lower end of the vertically-threaded member or bolt 8, and to this end it is shown as provided with parallel lugs 26, having apertures 27 and adapted to receive between them the apertured lug 12 on the lower end of the bolt 8. The inner faces of the lugs 26 are cut away at the sides, as indicated at 28, to reduce the width of their inner portions to the width of the groove 21, and thereby permit the engagement of the knuckle with said groove. A removable pivot-pin or pintle 29 extends through all three of these lugs and is secured in position by any suitable means—as, for instance, the split pins 30, as shown in Figs. 1 and 3. This pivot-pin constitutes the connecting devices between the upper and lower portions of the hanger, so that the door may be readily detached or taken down by removing these pins and as readily replaced. It will be

noted that these pins constitute the pivots whereon the door swings laterally with respect to the track, and the pivotal axis of this swinging movement is below the track and in the central plane of the track and 70 wheels.

It will be noted that by rotating the vertical threaded member or bolt 8 with respect to the wheel-support 5 or conversely the door may be raised or lowered relatively to the 75 track, so as to bring its lower edge into the proper or desired relation to the surface over which it travels. It will also be seen that by rotating the adjusting-sleeve 16 the door may be moved bodily toward or from the building 80 or other structure to which the track is applied. It will also be noted that the arrangement of the adjusting devices is such that they in no wise interfere with the free swinging of the door laterally upon its pivot-pins 85 29, the devices effecting the vertical adjustment constituting a part of the upper portion of the hanger, while those effecting the lateral adjustment constituting a part of the lower portion of the hanger, and the separable connecting-pivot being located between the two adjusting devices. Furthermore, in case of any bends or sinuosities of the track the wheel-support and wheel are free to turn about the vertical axis of the bolt 8, thus 90 permitting these parts to adjust themselves to the track by varying their relation to the normal plane of the door, and thereby preventing binding and excessive friction between the wheels and track. Referring 100 more particularly to the lower portion of the hanger, it will be seen that it is particularly adapted for application to doors of different thickness, since the two plates 13 and 14 are separate, and the connecting-bolts 15, by 105 which they are secured to the door, may obviously be of any desired length, while the sleeve 16 and pin 19 are of sufficient length to permit them to accommodate themselves to considerable variations of distance 110 between the plates 13 and 14.

In Figs. 3 and 4 I have shown another embodiment of my invention in which the lower portion of the hanger is identical with that already described and shown in Figs. 1 and 2, and therefore needs no further description. The upper portion differs from that already described in that the wheel frame or support here indicated by the reference-numeral 31, is provided with two track-wheels 32, arranged one in front of the other, thus constituting what is known as a "tandem" trolley or hanger. The body of this frame or support is provided between the two wheel-housings 33 with two guide lugs or flanges 34, having unthreaded apertures 35, through which the vertical threaded member or bolt, here indicated by the reference-numeral 36, passes in such a way as to be freely movable longitudinally therethrough. 37 represents a 130

- nut threaded upon the bolt 36 and supported upon one of the guide lugs or flanges 34, preferably the upper one, where it is readily accessible. Rotation of this nut in one direction or the other will obviously raise or lower the door relatively to the track. This particular form of construction of the devices for effecting the vertical adjustment has the advantage that it may be readily operated 5 without rotation of either the bolt or wheel-frame, so that the adjustment may be readily effected when all the parts are in position and connected. Of course the swiveling movement of the wheel-frame around the vertical axis of the bolt is present in this construction, as in the construction shown in Figs. 1 and 2, and this swiveling movement is of particular advantage in connection with the tandem arrangement of two wheels in a single supporting-frame, since the tendency to binding between the wheels and track is much greater with such a structure than with a single wheel. Of course the swiveling movement described involves a rotation of 15 the screw-threaded member, and when the part into which it is threaded does not rotate with said member, as in the construction shown in Figs. 1 and 2 and also in the construction shown in Figs. 3 and 4, when the nut 37 binds on the support 34, theoretically this involves a slight change in the vertical adjustment of the door; but in practice the angle of deviation of the hanger from a straight line of travel and the extent of rotation of the threaded member are so small 25 that the vertical movement of the door arising therefrom is imperceptible and too minute to have any practical effect upon the vertical adjustment.
- 40 I wish it to be understood that I do not desire to be limited to the exact details of construction shown and described, for obvious modifications will occur to a person skilled in the art.
- 45 Having thus fully described my invention, what I claim as new, and desire to secure by Letters Patent, is—
1. The combination, with a track, and a door, of a hanger supporting said door and comprising a frame, a track-wheel carried by said frame, a threaded part carried by said frame, a threaded member engaging said threaded part and thus supported by the frame, and means for pivotally connecting 50 said threaded member and the door, substantially as described.
2. The combination, with a track, and a door, of a hanger comprising a frame, a track-wheel carried by said frame, a threaded part 55 carried by said frame, an upright threaded member or bolt adjustably supported from the wheel-frame by said threaded part and having its lower end laterally deflected, and means for pivotally connecting the door to the 60 deflected lower end of said bolt in the ver-

tical plane of the track, substantially as described.

3. The combination, with a track, and a door, of a frame, a track-wheel mounted thereon, a non-rotating upright threaded member or bolt supporting the door and extending upward through an unthreaded portion of the wheel-frame, and a nut supported on said wheel-frame and engaging said threaded member to support the same and 70 adjust it vertically, substantially as described.

4. The combination, with a track, and a door, of a wheel-frame, track-wheels mounted the one in front of the other on said wheel-frame, an adjusting-bolt supporting the door and passing loosely upward through the wheel-frame between the wheels, so that said frame may swivel on said bolt, said bolt extending above the frame, and a nut mounted 80 on said extended end of the bolt and resting on top of the wheel-frame, substantially as described.

5. The combination, with a track, and a door, of a wheel-frame, a non-rotating upright threaded member connected to the door and supported from the wheel-frame, said wheel-frame being free to turn around the vertical axis of said threaded member to adjust itself to the track, and a threaded 90 part carried by said wheel-frame and engaging said threaded member, said engagement serving as a means for vertically adjusting the door, substantially as described.

6. The combination, with a track, and a door, of a hanger comprising an upper portion and a lower portion, a track-wheel mounted on the upper portion, the lower portion comprising separate plates secured to the sides of the door, a threaded adjusting 100 member supported by said plates and having a length sufficient to adapt it to doors of different thickness, and a part engaging said adjusting member, movable laterally thereby to adjust the position of the door and supported from the upper portion of the hanger, substantially as described.

7. The combination, with a track, and a door, of a hanger comprising an upper portion and a lower portion, a track-wheel 115 mounted on the upper portion, the lower portion comprising plates secured to the door, a supporting-pin carried by one of said plates and extending toward the other plate, an adjusting-sleeve passing through said other 120 plate and provided with an axial aperture to receive the supporting-pin, said adjusting-sleeve having a lateral adjustment in its supporting-plate, and a part supported from the upper portion of the hanger and engaging 125 said adjusting-sleeve so as to move longitudinally therewith, substantially as described.

8. The combination, with a track, and a door, of a hanger comprising an upper portion and a lower portion, a track-wheel 130

mounted on the upper portion, the lower portion comprising plates secured to the door, a supporting-pin carried by one of said plates and extending toward the other plate, an adjusting-sleeve threaded through said other plate, provided with an axial aperture to receive the supporting-pin and having a circumferential groove, and a knuckle detachably connected to the upper portion of the hanger 5 and engaging the groove of the adjusting-sleeve, substantially as described.

9. The combination, with a track, and a door, of a hanger comprising an upper portion and a lower portion, a track-wheel mounted on the upper portion, the lower portion comprising plates secured to the door, a supporting-pin carried by one of the plates and extending toward the other plate, an adjusting-sleeve threaded through said other 15 plate, having an axial aperture to receive the supporting-pin, provided with a circumferential groove, a knuckle-piece of yoke-like form engaging said groove, and a removable pivot-pin connecting said knuckle-piece and the upper portion of the hanger; substantially 20 as described.

10. The combination, with a track, and a door, of a hanger comprising an upper portion and a lower portion, a track-wheel 25

mounted on the upper portion, a vertical member adjustable in said upper portion, the lower portion secured to the door, a transverse threaded adjusting member mounted in the lower portion, a knuckle-engaging said transverse adjusting member, and a removable pivot-pin connecting said knuckle and vertically-adjustable member, substantially as described.

11. The combination, with a track, and a door, of a hanger comprising an upper portion and a lower portion, a track-wheel mounted on the upper portion, the lower portion being secured to the door, a transverse adjusting member having a threaded engagement with the lower portion of the hanger so as to move transversely with respect thereto when rotated, and a part supported from the upper portion of the hanger and having a swiveled connection with said adjusting-sleeve so as to move transversely therewith, 45 substantially as described.

In testimony whereof I affix my signature in presence of two witnesses.

PHILIP A. MYERS.
